UNITED STATES PATENT OFFICE

JOHN B. GLOWACKI, OF CHICAGO, ILLINOIS

FUSE INDICATOR

Application filed August 11, 1927. Serial No. 212,238.

This invention relates to an improved fuse indicator of the type in which a transparent cap is adapted to be discolored or displaced when a fuse on which the device is mounted 5 is blown, said indicating device serving to cool and extinguish the resultant flame even after the cap is removed.

It is an object of this invention to provide a simplified and improved indicator for use 10 on fuses and the like.

It is also an object of this invention to provide a fuse indicator so arranged to permit a slow emission of smoke to enable a blown fuse to be readily identified.

15 It is a further object of this invention to provide a fuse indicator with a plurality of outlets and with a screw device so arranged that a predetermined passage for the escape of smoke and the like from a blown fuse will 20 be provided.

It is an important object of this invention to provide a fuse indicator with a screw which serves as a means to provide a spiral passage for the escape of smoke or the products 25 of combustion resulting from a blown fuse element, said smoke adapted to be slowly discharged through outlet openings communicating with the threaded groove of the screw and through a chamber provided 30 within an apertured indicating cap when the device is provided with a cap.

Other and further important objects of this invention will be apparent from the disclosures in the specification and the accompanying 35 drawings.

This invention (in a preferred form) is illustrated in the drawings and hereinafter more fully described.

On the drawings:

40 Figure 1 is a side elevation of a fuse equipped with an indicator embodying the principles of this invention.

Figure 2 is a top elevation of the indicator and the fuse on which it is mounted.

45 Figure 3 is an enlarged vertical transverse section taken on line III—III of Figure 1.

Figure 4 is a transverse detail section of the indicator taken on line IV—IV of Figure 3.

50 As shown on the drawings:

The reference numeral 1 indicates a familiar type of cartridge fuse or any other type of inclosed fuse. The body of fuse 1 is provided with a threaded opening 2 for removably receiving the lower threaded shank 55 3 which is integrally formed at the lower end of a cylindrical tube or housing 4, the upper end 5 of which is of reduced diameter and is provided with a plurality of radially directed outlet apertures or passages 6. Integrally formed on the exterior of the housing 4 is a knurled flange or rib 7 affording a seat at 8 against which the lower open end of a gelatine cap 9 or the like is adapted to seat. The cap 9 is provided with an outlet aperture 10 in the rounded top thereof. If desired the aperture in the transparent cap may be omitted. The interior of the housing 4 is provided with a plain axial passage 11 which extends upwardly into the upper portion 60 15 and connects up with an intermediate plain passage 11^a which is slightly smaller than the passage 11. The exit passages 3 lead outwardly from said intermediate passage 11^a. The upper end of the housing portion 5 terminates in a threaded passage at 12 which is smaller than passage 11^a. Threaded tightly 65 20 into the upper end 5 of the housing 4 is a screw 13 which projects downwardly through the intermediate passage 11^a and enters the upper portion of the plain passage 11. The diameter of the intermediate passage 11^a is equal to the outer diameter of the threaded portion of the screw 13, thereby affording a spiral outlet passage from the upper portion 70 25 of the passage 11 to the radial outlet aperture 6 leading to the interior of the cap 9. Tightly secured into the lower end of the passage 11 is an axially passaged sleeve or plug 14 constructed of fibre or other hard insulating material. The lower end of the sleeve or plug 14 is provided with a beveled flange adapted to seat tightly against a beveled seat formed in the lower end of the housing 4. The sleeve 14 is provided for the purpose of obstructing 75 30 dust or hot metal particles, resulting from the blowing of a fuse element, from entering the passage 11 and clogging up the spiral escape passage leading to the outlet apertures 6. 80 35 40 45 50 55 60 65 70 75 80 85 90 95 100

In the use of the device the fuse is connected in an electric circuit in the usual way and is so positioned that the indicator may be readily seen. When too great a current flows in the circuit the fusible element within the fuse is melted or perhaps vaporized and in some cases a flame may be formed. The smoke and gaseous flames resulting from the blowing of the fuse element are adapted to escape through the passage 15 of the fibre plug 14 and enter the passage 11 where the velocity is checked by contact with the lower end of the screw 13. The plug 14 also serves as a stop to prevent dust particles and metal particles from entering the passage 11, thereby obviating plugging up of the spiral escape passage. The smoke or flames resulting from the blowing of the fuse element are now permitted to escape by way of the spiral passage afforded between the threaded shank of the screw 13 and the wall of the intermediate passage 11^a connecting the chamber 11 with the outlet passages 6. The smoke or flames gradually reach the outlet apertures 6 entering the chamber within the cap 9 at a diminished velocity. The smoke or flames resulting from the blowing of the fuse element on entering the cap 9 impinge against the inner face of the gelatine cap 3 acting to dis- color the same so that it will afford a visible signal to show an observer that a particular fuse has been blown. In case the action of the blowing of the fuse element is violent the pressure developed may blow the gelatine cap off of the housing 4, thereby also indicating in which fuse the element has been blown.

If the fuse element is blown by an electric current which is only slightly in excess of the current the circuit is intended to carry, instead of an explosive action, the smoke from the blown fuse element will emerge slowly through the spiral outlet passage and the apertures 6 to fill the cap 9 with smoke. The smoke in the cap will slowly discharge through the perforation 10 so that a fine steady stream of smoke will serve as an additional indication by which an observer may easily identify a blown fuse. As such a stream of smoke persists for some minutes after the blowing of the fuse, the observer is given sufficient time to reach the fuse and see the smoke even if the fuse is mounted in the cellar and the results of the blowing of the fuse is noted in some other part of the house due to the failure of lights or other circumstances.

The tortuous character of the passage afforded by the screw 13 leading to the outlet holes 6 is sufficient to prevent flames from finding their way to the outside of the fuse cartridge even in the case of a sudden and violent blowing of the fuse. Danger of fire resulting from the blowing of the fuse element is, therefore, reduced to a minimum.

65 Referring to Figure 3, it will be noted that

the lower end of the screw 13 projects downwardly into the passage 11 below the lower end of the intermediate passage 11^a. This arrangement is provided to obviate clogging of the spiral passage between the screw 13 and the wall of intermediate passage 11^a of the housing 4, since the end surface of said screw 13 acts as a stop surface for the accumulation of any of the products resulting from the blowing of the fuse element which may possibly find their way into the passage 11 through the plug passage 15. Clogging of the spiral outlet passage between the screw 13 and the wall of the intermediate passage 11^a is thus obviated.

I am aware that many changes may be made, and numerous details of construction may be varied through a wide range without departing from the principles of this invention, and I therefore do not purpose limiting the patent granted hereon, otherwise than necessitated by the prior art.

35 I claim as my invention:

1. The combination with a fuse having a threaded opening therein, of an indicator housing removably threaded in said opening, said indicator housing having a plurality of escape apertures and an axial passage therein, a screw threaded into one end of said indicator housing affording a spiral escape passage leading from the indicator housing passage to said apertures, a passaged plug secured in the other end of said indicator housing, and an apertured gelatine cap engaged on said indicator housing to inclose the apertured end thereof and said screw.

40 2. A fuse indicator comprising a body exteriorly threaded on one end to permit mounting of the same and having the other end of reduced diameter, said housing having a plurality of radial apertures in the reduced end thereof communicating with an intermediate axial passage in said housing, said housing also having a reduced threaded passage in one end thereof, a screw threaded into the threaded housing passage and projecting past the outlet apertures into an enlarged plain passage in the lower end of said housing, and an apertured cap engaged on said housing inclosing the screw and the apertured reduced end of said housing.

45 3. A fuse indicator comprising a housing having radial apertures in one end thereof and an axial passage of varying diameter one end of which is threaded, a screw adjustably engaged in the threaded end of said housing and projecting past said apertures, a passaged plug in the opposite end of said housing, and a cap engaged on said housing to inclose the screw and the apertured end of said housing.

50 4. A fuse indicator comprising a housing threaded at one end to permit mounting of the same, a knurled flange integrally formed on said housing, said housing having the

upper end thereof of reduced diameter and interiorly threaded, said housing also having a plurality of radially directed outlet apertures communicating with an intermediate plain axial passage which communicates with a slightly enlarged plain end passage, a screw adjustably threaded into the threaded end of said housing, with said screw projecting through the intermediate passage and past said radial apertures into the enlarged plain end passage of said housing, a passaged plug secured in the opposite end of said housing, and an apertured cap removably engaged on the housing with the open end of said cap seating on the housing flange.

5 5. A fuse indicator comprising a flanged housing having a graduated longitudinal passage and radial apertures therein, a screw threaded in one end of said housing and extending past said apertures, a passaged plug secured in the other end of said housing, and a gelatine cap on said housing inclosing the screw and the apertured end of said housing.

10 6. A fuse indicator comprising a housing having a graduated passage and apertures therein, a cap engaged on said housing, and adjustable means in said housing inclosed by said cap to afford a tortuous passage for the escape of the resultant products caused by the blowing of the fuse element in a fuse on which the indicator may be mounted.

15 20 25 30 35 40

7. A fuse indicator comprising a housing having radial openings therein and a graduated axial passage, means in one end of said housing to provide a tortuous passage communicating with said openings, and a passaged plug engaged in the opposite end of said housing to obviate clogging up of said tortuous passage by particles resulting from the blowing of a fuse element.

In testimony whereof I have hereunto subscribed my name.

JOHN B. GLOWACKI.
